UNITED STATES PATENT OFFICE.

JOHN HAYS HAMMOND, JR., OF GLOUCESTER, MASSACHUSETTS.

TREMOLO ATTACHMENT.

Application filed November 30, 1925. Serial No. 72,100.

This invention relates to musical instruments of the percussive type and especially to pianofortes and relates particularly to improved means for producing novel musical effects.

Broadly stated, it is the principal object of the present invention to provide improved means for producing a tremolo effect with an instrument of the damped compressional 10 wave type.

According to one feature of the invention, there is provided a resonating chamber having means therein for producing compressional waves and having modulating reflectors 15 for controlling the emission of sound with means for producing a tremolo effect. According to one modification of the invention a power driven mechanism is provided for oscillating the modulating reflectors 20 about a desired position of adjustment, and thus a novel tremolo effect may be obtained. According to another modification of the invention the modulating reflectors may be positioned by depression of a foot pedal, and 25 then by oscillating this pedal while keeping it in its depressed position, the modulating reflectors may be oscillated so as to produce a desired tremolo effect.

Other objects will appear from the following description taken in connection with the accompanying drawings in which

Figure 1 is a top plan view of a mechanism constructed in accordance with this invention;

Figure 2 is a front elevation partly in section of the mechanism shown in Figure 1;

Figure 3 is a bottom plan view of a detail of the mechanism shown in Figure 2;

Figure 4 is a front elevation of a detail 40 of the mechanism shown in Figure 2;

Figure 5 is a side elevation of the mechanism shown in Figure 4;

Figure 6 is a front elevation of a modified form of the invention;

Figure 7 is a side elevation of part of the mechanism shown in Figure 6.

Figure 8 is a bottom plan view partly in section taken on line 8—8 of Figure 7.

Figure 9 is an enlarged detail partly in cross section taken on line 9—9 of Figure 7.

Like reference characters refer to like parts in the several figures of the drawings.

In the following descriptions and claims,

parts will be identified by specific names for convenience of expression, but they are intended to be as generic in their application to similar parts or the equivalent construction as the art will permit.

In the form of the invention shown in Figures 1 to 5, the system is shown as applied to a grand piano 10 which is provided with the usual strings 11 mounted in a frame 12. A standard piano action 13 is provided for striking the strings 11 and is operated by the usual key board 14. A sounding board 15 is 65 located beneath the strings 11.

The piano is provided with three pedals 16, 17 and 18 mounted in a pedal block 19 which is supported from a second block 20 by two uprights 21 and 22. The block 20 is 70 carried by the frame work of the piano 10. The pedals 16 and 17 are connected to two rods 23 and 24 which control the usual sus-tenuto and loud pedal action of the piano.

The pedal 16 is connected to a rod 25 75 which has a bearing in the block 20 and the upper end of which engages one arm of a bell crank 26. This bell crank is pivoted to a member 27 which slides in a V shaped guide 28 and may be clamped in any desired position 80 in this guide by means of a set screw 30. The guide 28 is rigidly mounted upon the worm wheel 31 which is mounted for rotation upon a bracket 32 carried by the frame work of the piano. The worm wheel 31 meshes with a 85 worm 33 which is mounted on the shaft of the motor 34 which is rigidly secured to the frame work of the piano. The motor 34 may be connected to any suitable source of electric current by the conductors 35 and 36, through 90 a switch 37 which may be located at any convenient place on the frame work of the piano.

The other end of the bell crank 26 is pivoted to a link 40 to which is connected one end of a spring 41, the other end of which is secured to a bracket 42 carried by the frame work of the piano. The other end of the link 40 is pivoted to an arm 43 which is rigidly secured to a shaft 44 which is mounted in bearings 45 and 46. Secured to the upper end of the shaft 44 95 is a collar 47 which prevents it from sliding through the bearings. Rigidly secured to the shaft 44 are two arms 50 and 51 to which are pivoted two links 52 and 53, the other ends of which are connected to two rods 54 and 55. 100 Pivoted to these rods are two sets of arms 56

and 57 which are mounted upon an equal number of modulating reflectors 58 and 59 which are mounted for rotation about their longitudinal axes in the frame work of the piano.

The casing 10 is thus seen to be provided with controllable apertures for emitting sound in different directions respectively. The intermediate boundary walls of the casing are provided with a layer of sound insulating material 60 to render them substantially sound proof. The inner wall of the casing is provided with a compressional wave reflecting surface on its inner face as at 61, 62 (see Figure 2) which may be formed of sheet metal having a smooth surface, such as sheet aluminum or the like.

The modulating reflectors 58, 59 are of like construction and a description of one will suffice for all. Each is preferably in the form of an elongated, flat member having bevelled lateral edges and each is provided on its inner surface with a layer 63 of sound reflecting material, which may be of sheet metal having a smooth surface, such as sheet aluminum.

In the operation of the form of the invention shown in Figures 1 to 5, when the pianist depresses the pedal 16, the rod 25 is elevated, thereby rotating the bell crank 26 in a counter-clockwise direction. This causes the link 40 to be moved to the right thus rotating the arm 43, the shaft 44 and the arms 50 and 51 in a counter-clockwise direction as seen in Figure 3. This will cause the links 52 and 53 to be moved to the right thus moving the rods 54 and 55 to the right. This will cause the sets of modulating reflectors 58 and 59 to be gradually closed, or they may be held in any intermediate position by stopping the motion of the pedal 16.

If it is desired to produce a tremolo effect, the pianist closes the switch 37, thereby starting the motor 34 which rotates the worm 33, thus turning the gear 31 at a pre-determined speed. This will cause the member 27 to be rotated about the center of rotation of the gear 31 thus causing the pivot point of the bell crank 26 to be rotated in a like manner.

As the position of the rod 25 is held constant by means of the pressure of the foot on the pedal 16, the end of the bell crank 26 which rests on the top of this rod, will be kept at a uniform place, i. e., at a desired position of adjustment. The pivot point of this bell crank is now rotated by the gear 31, and the other end of this bell crank will thus be caused to oscillate about said desired position of adjustment, i. e., the position it would have if the motor 34 were not running. This oscillation will be transmitted by means of the link 40 through the shaft 44 to the modulating reflectors 58 and 59, thus causing them to be rapidly oscillated about the position they would be in if the motor 34 were not running.

As the pedal 16 is moved, it will move the upper end of the rod 25, thus moving the mean position of oscillation of the lower end of the bell crank 26 which will cause the modulating reflectors 58 and 59 to be operated about a different mean position.

It is thus seen that the mean position of the modulating reflectors will be controlled by the position of the pedal and that the oscillation will take place about this mean position when the tremolo motor is put in operation.

In the modified form of the invention shown in Figures 6 to 9, the piano 10 is of the same construction as that shown in Figures 1 to 2 and is provided with the two sets of modulating reflectors 58 and 59 which are operated from the shaft 44 by means of the link 40 as shown in Figures 1, 2 and 3.

In the modified form of the invention shown in Figures 6 to 9, the link 40 is connected to one arm of a bell crank 70 which is pivoted at 71 to a bracket 72 carried by the frame of the piano 10. Secured to the bracket 72 is a block 73 which carries two uprights 74 and 75, to the lower ends of which is secured a pedal block 76. In this block are mounted three pedals 80, 81, and 82 which actuate three rods 84, 85 and 86 respectively. These three rods 84, 85 and 86 control the standard soft pedal action sostenuto and loud pedal action of the piano 10.

To the other end of the bell crank 70 is pivoted a link 90, the other end of which is pivoted to a member 91 (see Figures 7 and 8). This member is rotatably mounted upon a shaft 92 which is carried by a bracket 93 mounted upon the pedal block 76. Mounted on the member 91 is a roller 94 which can roll in a slot 95 provided in a plate 96 which is secured to the under surface of a pedal 97. This pedal is rotatably mounted upon a member 98 which in turn is rotatably mounted upon the rod 92.

In the operation of the modified form of the invention shown in Figures 6 to 9, when the pianist desires to close the modulating reflectors 58 and 59, he depresses the inner end of the pedal 97, thus causing the rod 90 to be pulled downwardly which rotates the bell crank 70 in a counter-clockwise direction about the pivot 71. This causes the link 40 to be moved to the right thus closing the modulating reflectors 58 and 59 in a manner similar to that described in connection with Figures 1 to 3.

If he desires to produce a tremolo effect he moves his foot rapidly to the right and left, keeping it in the same plane, however. In this way the pedal 97 and the plate 96 will be moved with respect to the roller 94, causing it to follow the curve of the slot 95 thus oscillating the member 91 with respect to the pedal 97. This will cause the link 90 to be rapidly moved up and down about

5 a mean position determined by the initial position of the pedal 97. This, by means of the bell crank 70, link 40, etc., will cause an oscillation of the modulating reflectors 58 and 59 about the mean position which they would be in if the pedal 97 is in a central position.

10 In this way it is seen that the modulating reflectors may be opened and closed in the usual manner by rotating the pedal about the rod 92, and that by rotating the pedal in a plane perpendicular to the first rotation, a tremolo effect may be produced in the modulating reflectors the speed of which can be 15 controlled by the speed of the oscillation of the pianist's foot.

20 The invention upon which this application is based is broader than the specific embodiment shown and described for the purpose of illustrating at least one of the ways in which it may be employed. The scope of the invention is therefore to be understood as not being limited by the present specific description. I intend no limitations other than those 25 imposed by the claims.

What is claimed is:

1. An instrument for producing damped compressional waves, comprising a plurality of strings tuned to the notes of the musical scale, a plurality of hammers for setting said strings into vibration by percussion, a casing surrounding said strings, said casing having apertures, a plurality of modulating reflectors rotatably positioned in said apertures, each having a compressional wave reflecting surface on its inner face, means for adjusting said reflectors into desired angular displacement, and means for oscillating said reflectors about said position of adjustment.

40 2. An instrument for producing damped compressional waves, comprising a vibratory element, a casing therefor having controllable apertures, a plurality of sound reflectors rotatably positioned in said apertures for controlling the direction of sound waves produced, means for adjusting said reflectors into desired position, and means for oscillating the reflectors about said desired position of adjustment.

45 3. In a musical instrument, the combination with means for producing musical sound by percussion, of a casing having oppositely disposed controllable apertures and substantially soundproof intermediate boundary walls, a plurality of modulating reflectors positioned in said apertures for variably reflecting the sound emitted through said apertures, a pedal operatively connected to said reflectors for adjusting the same into desired angular displacement, and power driven means for oscillating said reflectors.

50 4. In a musical instrument, the combination of a plurality of modulating reflectors for directing sound waves, a control device

55 for variably adjusting said reflectors, and power driven means for intermittently vibrating the reflectors to produce a tremolo effect.

5. In a musical instrument for producing music, the combination with a source of sound, a substantially sound proof casing surrounding said sound source and having apertures therein, and having a plurality of centrally pivoted metal lined reflectors positioned in said apertures and arranged to control the emission of sound therethrough, and power driven means for oscillating said reflectors.

6. In a musical instrument, a source of sound, a casing surrounding said source, said casing having oppositely disposed apertures and substantially soundproof intermediate boundary walls, a plurality of centrally pivoted metal lined reflectors positioned in each of said apertures, means for adjusting the angularity of said reflectors with respect to said sound source, and power driven means for oscillating said adjusting means.

7. In a musical instrument, the combination with a resonating chamber, means positioned therein for producing damped compressional waves, and means for controlling emission of the waves from the chamber to produce musical sound, of means for vibrating said emission controlling means.

8. In a musical instrument, the combination of a resonating chamber having a sound insulating wall for suppressing sound, a layer of sound reflecting material on the inner face of said wall, a vibratory element within said chamber, a plurality of modulating reflectors positioned in other walls of the chamber for reflecting sound waves produced by said element in desired directions, and means for vibrating the reflectors.

9. An instrument for producing damped compressional waves, comprising a plurality of strings tuned to the notes of the musical scale, a plurality of hammers for setting said strings into vibration by percussion, a substantially sound proof casing surrounding said strings, said casing having apertures, a plurality of centrally pivoted modulating reflectors positioned in said apertures for variably reflecting sound emitted through said apertures, a pedal operatively connected to the reflectors for adjusting said reflectors into desired angular displacement, and means for oscillating said reflectors about said position of adjustment.

10. An instrument for producing damped compressional waves, comprising a vibratory element, a substantially soundproof casing therefor having controllable apertures, a plurality of centrally pivoted sound reflectors positioned in said apertures for controlling the direction of sound waves produced, a pedal operatively connected to the reflectors.

for adjusting said reflectors into desired position, and means for oscillating the reflectors about said desired position of adjustment.

11. In a musical instrument, the combination with a plurality of tuned elements, of a substantially sound proof casing having oppositely disposed controllable apertures and substantially soundproof intermediate boundary walls, a plurality of centrally pivoted modulating reflectors positioned in said apertures for variably reflecting the sound emitted through said apertures, a pedal, a bell crank lever operatively interconnecting the pedal and the reflectors for adjusting the reflectors into desired angular displacement, and a power driven gear for oscillating the pivot of said bell crank.

12. In a musical instrument, the combination with a combination of a plurality of modulating reflectors for directing sound waves, a control device, a connection between said control device and said reflectors including a bell crank lever, and a power driven gear for intermittently vibrating the pivot of said bell crank to impart vibratory movement to the reflectors.

13. In a musical instrument, the combination with a resonating chamber, means positioned therein for producing damped compressional waves, and means for controlling emission of the waves from the chamber to produce musical sound, of a pedal for adjusting said controlling means, and means for modifying the adjustment of the controlling means.

14. In a musical instrument, the combination of a resonating chamber having a sound insulating wall for suppressing sound, a layer of sound reflecting material on the inner face of said wall, a vibratory element within said chamber, a plurality of modulating reflectors positioned in other walls of the chamber for reflecting sound waves produced by said element in desired directions, a pedal operatively connected to the reflectors and means to modify the adjustment of the reflectors.

15. In a musical instrument the combination with a piano of a casing having sound openings, a plurality of movable closures for said openings, and means for oscillating said closures about a given median position.

16. In a musical string instrument means for suppressing the sound produced thereby including a casing having openings for the

emission of sound, a plurality of movable closures for variably controlling the emission of sound through said openings, and means for oscillating said closures about a definite median position.

17. In a piano a plurality of strings, a sounding board adjacent said strings, a casing having sound openings and including a substantially soundproof layer for effectively suppressing sound, a pair of groups of normally opened centrally pivoted closures for said openings, each group of closures being parallel with and spaced from the sounding board and forming when closed in combination with the casing a pair of resonant chambers, manually operable means for actuating said closures to vary the intensity of musical sound emitted from the instrument, and manually controlled means for oscillating said closures.

18. In a musical instrument of the percussive type the combination with tuned strings of a casing having oppositely disposed apertures, controllable closures for said apertures, said casing having boundary walls intermediate said apertures, each provided with a layer of substantially soundproof material, and means for oscillating said closures.

19. In a musical instrument of the percussive type the combination with tuned strings for producing sound, of a casing having oppositely disposed apertures, controllable closures for said apertures, said casing having boundary walls intermediate said apertures, each provided with a layer of substantially soundproof material, means for variably positioning said closures, and automatic means controlled at the will of an operator for oscillating said closures about a predetermined position.

20. In a musical instrument of the percussive type the combination with tuned strings of a casing having apertures, controllable closures for said apertures, means for variably positioning said closures to control the emission of sound from the instrument, and automatic means controlled at the will of an operator for continuously oscillating said closures about a predetermined position.

Signed at New York in the county of New York and State of New York this 27th day of November, A. D. 1925.
